SECTIONAL GRATING

Harold Nagin, Pittsburgh, Pa., assignor to Reliance Steel Products Company, McKeesport, Pa., a corporation of Pennsylvania

Application September 15, 1941, Serial No. 410,941

5 Claims. (Cl. 189—82)

This invention relates to sectional grating, and particularly to grating which is made of structural units which can be expeditiously joined to adjacent units when laid in place, and can be readily removed from such position should it prove desirable to do so. The invention resides in the particular unit itself, in the assembly of the units, and also in the means for joining adjacent units firmly together in such manner that a unit can be readily detached from the adjoining units and removed and the same or another unit put in place of the unit removed.

In some instances it is desirable to cover an area with grating, the area being too large to be covered by a grating made in one piece. It is the custom to make the necessary area of grating in units or sections, each unit being of a size which can be readily and economically fabricated in a shop and then transported to the site to be covered. When placed in final position the grating may rest on suitable spaced-apart supports, or it may rest on the ground or other continuous surface. It is sometimes necessary that a portion of the grating covering the area be removed either to gain access to a surface or to a space below the area, or a portion of the grating may be damaged and have to be replaced. This requires that the units be joined in such manner that any unit or any number of units be readily removable from its position in the grating area and readily replaceable, and that the units be interchangeable. Difficulty has been encountered in this respect as it must be borne in mind that the means employed for fastening the units together shall provide a strong and rigid joint, be secured to the unit itself without causing appreciable diminution in the strength of the unit, and a joint that can be expeditiously secured or unfastened by unskilled help and sometimes under extremely adverse conditions. It is also advantageous on occasions to space each unit apart from the adjoining units. These requirements are all met in my invention.

In the drawings wherein I have shown for purposes of illustration only the present preferred embodiment of my invention:

Figure 1 is a plan view of a grating unit;

Figure 2 is a sectional view along the line II—II of Figure 1;

Figure 3 is a view, on a larger scale than Figure 1, showing a junction area where portions of three units are joined together;

Figure 4 is a view in elevation along the line IV—IV of Figure 3;

Figure 5 is a sectional view along the line V—V of Figure 4;

Figure 6 is a plan view of a wing bar;

Figure 7 is a view in elevation of the wing bar shown in Figure 6;

Figure 8 is a diagrammatic plan view showing the units in position covering an area;

Figure 9 is a plan view of another form of wing bar;

10 Figure 10 is a plan view of still another form of wing bar; and

Figure 11 is a detail of a portion of a unit slightly different from that shown in Figure 1.

In the drawings, Figures 1 through 7, there is shown a section or unit A of grating which is made from spaced-apart rectangular metal bearer bars 2 which run on edge substantially parallel to each other, and longitudinally of the unit and for the length thereof. The outside bearer bars are referred to as "side bars" and designated by the numeral 3. At suitable intervals the bearer bars are joined by the metal cross-bars 4 which are arranged at substantially right angles to the bearer bars and are joined thereto in any suitable manner, such as by welding, and usually by electric pressure resistance welding. Usually, but not always, the tops of all the bars are in a common plane. The bottoms of the longitudinal bearer bars are joined

25 by stiffeners 5 which are metal bars secured as by electric pressure resistance welding to the bearer bars, and extend substantially at right angles thereto. The stiffeners extend the full width of the unit and are more widely spaced than are the cross-bars. In certain light weight units the stiffeners can be dispensed with.

30 At each end of the unit, end bars 6 are provided. They are substantially the same depth as the bearer bars 2 and are welded to the ends thereof. The side bars 3 and the end bars 6 are welded together to form a continuous outside member or frame.

Attached to the outside member at predetermined intervals are connector members or wing bars 7 of crenelated shape formed from metal bars of approximately the same depth as the bars forming the outside members. The wing bar 7, which is shaped as shown in Figures 6 and 7, has two spaced-apart and outwardly directed

50 U-portions 8 and 9 intermediate the contact portions 10 and 11. This provides two land portions 12 and 13 on one side, and three contact portions 10, 11 and 14 on the other side and which lie in a common plane. The extreme ends of the portions 10 and 11 are tapered as shown. The lands lie ad-

jacent the outside member of one unit and the portions lie flat against the outside member of an adjacent unit. Each wing is secured to the outside member by rivets 15 which pass through the lands 12 and 13 and through the side bars and end bars forming the outside member or it may be secured in any other convenient manner, as by welding. The wings are secured to the end portions in staggered relation, so that when a unit is turned end for end the wings are in the same relative positions, and when two units are butted the wing bars from the end of one unit will lie between the wing bars in the abutting end of the other unit. The lands and contact portion are spaced apart a distance equal to the desired space between adjacent units. This provides automatic and accurate spacing of the units.

Band clips 16 which embrace the outside member are provided at intervals along the outside members. The clips are dimensioned so as to closely but slidably embrace the outside member of one unit, and the portions 10 or 11 of a wing 7 of an adjoining unit, and are so positioned along the outside member as to cooperate with the wing bars of adjoining units. The clip is shown in securing position in Figure 3. After the units are assembled, and the clips have been positioned over the end portions of the wing bar, the end portions of the wing bar adjacent the clip are bent outwardly and away from the outside member as shown in dotted lines and designated 10a in Figure 3.

The units are placed over the support in staggered relation to each other as shown diagrammatically in Figure 8. The plan view of the assembled units resembles the elevation of an ordinary brick wall in which the end joints are broken but the longitudinal joints are not. If desired, however, the longitudinal joints could be broken instead of the end joints, in which case the end joint would be continuous. If this arrangement was adopted the wing bars on the longitudinal side of the bars would have to be staggered to cooperative position.

It will be observed that the wing bars have two lands on one side and three contact portions on the other. This makes a very strong type of fastening device which has no tendency to bend or get out of line. The wing bars can be made heavier than the outer members and thus form a stronger connection without materially increasing the weight of the unit. Instead of having the wing bars crenelated the bar 7a can be serpentine in form with the end portions flat as shown in Figure 9.

The wing bar 17 shown in Figure 10 has one U-shaped portion 18 and two outwardly directed contact portions 19 and 20. The land or bottom 21 of the portion 18 is riveted to the outer member by rivets 22.

In Figure 11 there is shown a unit which instead of being formed of longitudinal bars and transverse cross-bars is formed from an outside member or frame comprising two longitudinal spaced-apart side bars 23, and two end bars 24 joining the ends of the longitudinal bars. The intermediate bearer bars and cross-bars of the structure shown in Figure 1 are replaced in this form by a metal mesh 25 which is secured to the frame. Otherwise the unit and the means for fastening the units together to cover an area are the same as that hereinbefore described.

While I have described certain preferred embodiments of my invention, it will be understood

that this is merely by way of illustration and that various changes and modifications may be made in the structure within the scope of the following claims.

5 I claim as my invention:

1. For use in a section grating composed of like separable units detachably joined together, said separable units having a frame member around the unit, means for connecting said units in a manner permitting ready removal and replacement of any unit, said means including a crenelated wing bar secured to the frame member of one unit, each bar having a land which is rigidly fastened to the frame of one unit, and contact portions spaced from the land portion, and band clips slidably mounted on the frame member for engaging the contact portions of wing bars fastened to an adjoining unit.

2. For use in a section grating composed of

20 like separable units detachably joined together, said separable units each comprising spaced apart longitudinal bearer bars, transverse cross bars secured to the tops of the bearer bars and extending across the unit, end bars extending the 25 width of the unit and secured to the ends of the longitudinal bars, the outer bearer bars and end bars being joined to form an outside member, means for connecting said units in a manner permitting ready attachment of and removal of a 30 unit, said means including crenelated wing bars secured to adjacent outside members at co-operating locations to permit staggering of joints, each of said crenelated bars having contact portions extending in the direction of portions of the outside member to which it is attached and spaced from the outside member, and band clips for slidably engaging the contact portion of a wing bar and embracing the outside member of an adjoining unit.

40 3. For use in a section grating composed of like separable units detachably joined together, said separable units each comprising spaced apart longitudinal bearer bars, transverse cross bars secured to the tops of the bearer bars and ex-

45 tends across the unit, end bars extending the width of the unit and secured to the ends of the longitudinal bars, the outer bearer bars and end bars being joined to form a continuous frame member, means for connecting said 50 units in a manner permitting ready attachment of and removal of a unit, said means including serpentine wing bars secured to adjacent frame members at co-operating locations to permit 55 staggering of joints, each of said serpentine wing bars having contact portions extending in the direction of portions of the outside member to which it is attached and spaced from the outside member, and band clips for slidably engaging the contact portion of a wing bar and the frame member of an adjoining unit.

60 4. A structural unit to be joined to a plurality of similar units to form a sectional grating, said unit comprising a rectangular grating having side bars and end bars, connector members secured to the side and end bars, each of said connector members being integrally formed and having at 65 least two land portions which contact the bar to which the connector member is secured and at least three contact portions for engaging a 70 bar of a similar adjacent unit, the side bars and end bars having slidable clips thereon anchored against transverse separation therefrom and located intermediate the connector members which engage certain of the contact portions of the connector members of adjacent units.

5. A structural unit to be joined to a plurality of similar units to form a sectional grating, said unit comprising a rectangular grating having side bars and end bars, connector members secured to the side and end bars, each of said connector members being integrally formed and having at least two land portions in a common plane which contact the bar to which the connector member is secured and at least three contact portions in

common plane for engaging a bar of a similar adjacent unit, the side bars and end bars having slid able clips thereon anchored against transverse separation therefrom and located intermediate the connector members and adapted severally to engage contact portions of the connector members of adjacent units.

HAROLD NAGIN.
